UNITED STATES PATENT OFFICE.

FREDRIK LJUNGSTRÖM, OF BREVIK, LIDINGON, SWEDEN, ASSIGNOR TO AKTIEBOLAGET LJUNGSTRÖMS ÅNGTURBIN, OF STOCKHOLM, SWEDEN, A CORPORATION.

REGENERATIVE HEAT-EXCHANGE DEVICE.

Application filed April 11, 1921, Serial No. 460,600, and in Sweden April 23, 1920.

My invention relates to heat exchange devices of the so-called "regenerative" type wherein one fluid passes in contact with the surface of a substance and gives off heat to the substance, whereafter another fluid passes into contact with the same surface and is heated.

One object of my invention is to provide an effective, operable and highly efficient heat exchange apparatus of this type. Further objects of the invention are: to provide a heater of the type referred to having a large heat absorbing and heat rejecting surface for a given weight and volume of heater; to provide an arrangement in which flow is unrestricted and friction is small; to prevent leakage or short-circuiting of fluids between passages for different fluids, particularly at points where inlet and outlet channels are adjacent the substance serving to absorb and reject heat; and to provide an apparatus capable of supplying a uniform quantity of air to a boiler furnace so that furnace combustion is even.

Further objects will be apparent as the description proceeds.

The invention consists, in one feature thereof, in the combination with a body or mass of regenerative material composed of metal units, of means for continuously altering the relation of supply and discharge channels to sections of the metal units to effect a constant continuous and uniform flow and heat transfer in the heat transfer device. In order to obtain continuous and uniform flow of fluids, I provide an arrangement such that, at the times when there is change of communication of regenerative passages between channels for different fluids, such change of communication does not disturb continuity of flow; and, to this end, preferably employ continuously operating mechanism so acting that, at any given time of operation, a section of the regenerative material constitutes a part of the path of flow of the fluid to be heated while another section forms part of the path of flow of the heated fluid and while still another portion of the regenerative material is changing communication with respect to the inlet and outlet channels for the different fluids between which heat is exchanged. Further, the invention consists in the combination of a frame-work, supply and discharge channels for heating and heated

fluids, means for effecting relative movement between the frame-work and the channels and regenerative material, preferably metal, in the frame-work arranged to obtain a large surface for a small weight and means to prevent, to a high degree, leakage between channels.

Further features of the invention consist in the employment—in heaters of the type referred to—of metal plates, flat or corrugated, arranged to form a multitude of small passages for flow of heating and heated fluids, the passages being thus surrounded by heat absorbing material, the passages being preferably arranged in the general line of flow through the apparatus and of equal cross-section and parallel to each other to obtain a maximum heat transfer effect with a minimum friction loss. To facilitate formation of passages of equal cross-section, I, in some cases, divide the frame-work into chambers each containing a unit of regenerative mass.

The accompanying drawing illustrates an apparatus embodying various features of my invention, in five figures, of which: Fig. 1 shows the apparatus, in cross-section, applied to the preheating of air for combustion in a boiler furnace; Fig. 2 is a section taken on line 2—2 of Fig. 1; Fig. 3 is a section taken on line 3—3 of Fig. 2; Fig. 4 is a section taken on line 4—4 of Fig. 2 and Fig. 5 is a section taken on line 5—5 of Fig. 1.

Referring more particularly to Fig. 1, numeral 1 designates the furnace of a boiler which is supplied with preheated air for combustion. Gaseous products of combustion leave the rear of the furnace and pass through return tubes 2 and thence into passageway 3, which serves both as an up-take for the flue gases and a supply channel for the hot gases, to a regenerative heating device designated generally by numeral 15.

The regenerative heating device comprises what I term a frame-work serving to support or carry a regenerative material. In the embodiment shown the frame-work, designated by numeral 4, is of cylindrical outer form and is divided by concentric walls 21 and radial walls 22 (see Fig. 2) into a series of radially and circumferentially disposed chambers 23 in which the regenerative material is placed. The regenerative material is arranged to form a series of passages 19 (see Fig. 4) through the frame-work for flow of

fluids. Preferably a multitude of passages are formed, as shown.

The flue-gases after passing through some of the passages formed by the regenerative material and after having given off heat to the regenerative material pass out through discharge channel or spent gas outlet 6.

The air for combustion which is the fluid to be heated enters through supply channel or cooled air inlet 5, passes through some of the passages formed by the regenerative material, which, at any given time are other than those through which the flue gases pass and thence passes through passageway 7 which, with respect to the regenerative device is a discharge channel or outlet for the fluid to be heated and, with respect to the furnace 1, is a part of the air supply channel.

The channels or passageways 3, 5, 6 and 7 are formed in a cylindrical stationary casing divided into halves by a stationary partition wall 10 serving as a separating wall between the channels for the fluid to be heated and the fluid giving off heat. Below the framework 4 the partition 10 is in the embodiment shown, in part formed by a support and casing for a driving mechanism 8 serving to move framework 4 relatively to the various supply and discharge channels.

The frame-work is situated partly in the path of air which includes channels 5 and 7 and partly in the path of flue gases which includes channels 3 and 6.

In the position shown, the regenerative material in the frame-work at the left hand side is heated by flue gases and rises in temperature. As the frame work is rotated by driving mechanism 8 the heated regenerative material is caused to pass into the path of air through channels 5 and 7 where the regenerative material gives off heat to the air. On further rotation the section of regenerative material under consideration passes again into the path of hot flue gases and is again heated.

The regenerative material consists of a multiplicity of metal members which may be in the form of straight plates as shown in Fig. 2 in several of the chambers 23^a at the right hand side of the frame-work and lettered 24, or corrugated plates as shown in chambers 23^c and lettered 25, the plates being placed edgewise to the flow of gases through the frame-work, or in other forms. The metal members are preferably of such form and so arranged as to provide a series of continuous parallel passages of uniform cross-section through the frame-work.

When corrugated plates are used, they are mounted in such manner that the corrugations of two adjacent surfaces cross each other as shown to the left of Fig. 1.

With flat plates, the best results are obtained if the distances between the plates are the same in all places. The division of

the rotor into radial chambers and the placing of numerous plates in the chambers either peripherally or radially gives equal or approximately equal distances between plates both at the outer and inner parts of the frame-work. By using thin metal plates a large surface of heat absorption and heat rejection is obtained for a relatively small volume of regenerative material and thus an exceedingly small size of heater is possible for a large heat transfer.

By placing the metal members perpendicular to the planes determined by the upper and lower ends of walls 21 and 22 and the outer cylindrical drum of the frame-work, that is, perpendicularly to the planes determined by the open ends of the frame-work so that the metal members and the passages formed by the same are in the line of flow of gases through the regenerative heating device, the friction of gases against the regenerative material is small as compared to previously proposed arrangements in which fire clay regenerative material is placed crosswise to the flow of gases and arranged to form a tortuous passageway for fluids. With metal members arranged edgewise in the line of flow, the cross-section of passage 19 is very small and yet the friction is low.

Although I have shown different arrangements of regenerative material in different chambers of the frame-work, this is principally done for sake of illustration. In practice it is customary to use the same type of regenerative material in all chambers of a frame-work.

To obtain an efficient heater it is necessary to have means to prevent leakage between the channels for air and the channels for gas. In order to prevent leakage between channels 5 and 6 and correspondingly between channels 3 and 7, at those places in the frame-work which are open to a passage of gases, I employ what may be termed sector plates designated by numeral 30, the term "sector" being chosen because the plates used are of substantially sector shape. The sector plates are of such size that they cover any radially disposed series of chambers 23 as that series passes past the sector plate. There are two sector plates above the frame-work and two below, the radial center lines of the sector plates being in the plane of partition wall 10. The sector plates under the frame-work are directly below those above the frame-work. Each chamber 23 is therefore cut off entirely from communication with both gas and air channels at that point in its travel when its forwardly disposed radial wall with respect to the direction of travel is just about to enter one channel and its rearwardly disposed wall has just left the other channel, considering, for the moment, that the channels, as they are extended into the frame-work, are determined by the outer effective

edges of the sector plates. The sector plates by thus successively closing each and all of the chambers as the chambers change communication from one channel to the other at 5 all times prevent passage of fluid from one channel, past the edge of partition 10, through a part of the chambers and into the other channel.

The sector plates above the frame-work 10 bear against walls 21 and 22 by their own gravity, being fitted for this purpose, with center line flanges 18 loosely fitting into grooves 17 in the forked lower portion of the upper part of partition 10. The sector plates 15 below the frame-work are also fitted with center line flanges 18 fitting into grooves in the lower part of partition 10. The latter sector plates are held in contact with walls 21 and 22 by weights 12 attached to levers 20 14 pivoted on partition 10 intermediate their ends, and extending into holes 13 in the flanges 18, whereby the downward force of weights 12 gives an upward pressure to plates 30.

25 At the center of the frame-work, where covering plates 11 are attached over the top and bottom of the hollow center core of the frame-work, the partitions 10 or parts attached to the partitions are arranged so 30 closely to covering plates 11 that leakage is prevented. It will be readily apparent that no matter how carefully an apparatus may be constructed some leakage will take place and, therefore, what I mean by preventing 35 leakage is to prevent leakage to so high a degree that a thoroughly efficient apparatus is obtained and losses due to unavoidable leakage are practically negligible.

It will be seen that the sector plates are, 40 in reality, stationary valves, which together with the driving mechanism causing rotation of the rotor, effect passage of the hot gases in contact with given plates for a determined period and then passage of air to be heated in contact therewith for another 45 period.

In order to prevent by-passing of fluid around the outside of the frame-work without passing through channels 19, I show angular parts 27, together forming an annular ring extending around the frame-work, resting in a recess in a shoulder 26 formed in the regenerator housing and bearing by their own weight on the top of the outer drum of 55 the frame-work.

While I have shown and described one apparatus embodying my invention, it is obvious that many embodiments falling within the scope of the invention are possible. 60 Many arrangements of regenerative material are possible. Plates with ribs may be used instead of corrugated plates. Relative movement between the frame-work and the inlet and outlet channels may be effected in various ways. Instead of moving the frame-

work, the inlet and outlet channels or passageways may be moved. The frame-work may rotate, oscillate or have rectilinear movement.

As the regenerative heat exchange device 70 with parallel straight plates constitutes one embodiment and the regenerative heat exchange device with cross-wise placed corrugated plates constitutes a second embodiment of the invention, I elect to claim the 75 straight plates herein and reserve the claiming of the cross-wise placed corrugated plates for a separate application Serial No. 579,545, filed August 3, 1922, the generic invention, however, being claimed in this application. 80

What I claim as new and desire to secure by Letters Patent of the United States is:—

1. An apparatus of the class described comprising a plurality of chambers each having a multiplicity of heat exchanging 85 plates therein and means for automatically passing hot gases in contact with said plates for a determined period and then passing air to be heated in contact therewith for another period. 90

2. An apparatus of the class described comprising a plurality of chambers each having a multiplicity of nested heat exchanging plates therein and automatically controlled means for alternately passing hot 95 gases and cool air in contact with said plates for determined periods of time, the apparatus being so arranged that the waste gas flows continuously therethrough in one direction and the air to be heated also flows 100 continuously in one direction.

3. An apparatus of the class described comprising a plurality of chambers each having a multiplicity of metal heat exchanging plates therein, a hot gas inlet and a spent 105 gas outlet common to said chambers, a cool air inlet and a heated air outlet common to said chambers and means automatically controlling the passage of both gas and air to and from said chambers at regular time intervals. 110

4. An apparatus of the class described comprising a plurality of chambers each having a multiplicity of nested metal plates 115 therein arranged to form a multitude of passages having a vast surface and automatically controlled means for alternately controlling the passage of gas and air respectively through each of said chambers. 120

5. A regenerative heat exchange device comprising supply and discharge channels for a fluid to be heated and a fluid giving off heat, a metal regenerative mass arranged to form a multitude of passages through the same, means to change communication between said passages and different channels, the arrangement being such that at a given time of operation, a multitude of said passages forms part of the path of flow of the fluid to be heated, while another multitude 125 130

- of passages forms part of the path of flow of the heating fluid and while still other passages are momentarily out of communication with either path of flow as they 5 change communication with respect to the channels, so that there is a continuous uniform flow of fluid through the heat exchange device and substantially no intermixture of the different fluids.
- 10 6. A regenerative heat exchange device comprising walls forming compartments, channels for a fluid to be heated and a fluid giving off heat, means to change communication between any of said compartments 15 and different channels, metal regenerative material in said compartments consisting of members placed in the general line of flow through the compartments, the arrangement being such that, at any one time of operation, 20 a plurality of compartments forms part of the path of flow of the fluid to be heated, while another plurality of compartments forms part of the path of flow of the heating fluid and while still other compartments 25 are changing communication with respect to the channels, so that there is a continuous uniform flow of fluids through the heat exchange device and substantially no intermixture of the different fluids.
- 30 7. A regenerative heat exchange device comprising metal regenerative material having passages through the same, channels for a fluid to be heated and a fluid giving off heat, means to change communication between any of said passages and different channels, the arrangement being such that, 35 at a given time of operation, a plurality of the passages forms part of the path of flow of the fluid to be heated while another plurality of the passages forms part of the path of flow of the heating fluid and while still other passages are momentarily out of communication with either path of flow.
- 40 8. A regenerative heat exchange device comprising metal regenerative material having a multitude of passages through the same, channels for a fluid to be heated and a fluid giving off heat, continuously moving means to change communication between 45 said passages and different channels and operating so that, at any one time of operation, a multitude of the passages forms part of the path of the fluid to be heated while another multitude of passages forms part 50 of the path of the heating fluid, while still other passages are changing communication with respect to the channels and so that there is a continuous uniform flow of fluids through the heat exchange device and substantially no intermixture of the different fluids.
- 55 9. A regenerative heat exchange device comprising metal regenerative material having a multitude of passages through the same, channels for a fluid to be heated and a fluid giving off heat, 60 means to rotate the rotor and operative to change communication between any of said passages and different channels, the arrangement being such that, at any one time of operation, a plurality of the passages forms part of the path of flow of the fluid to be heated, while another plurality of the 65
- a fluid giving off heat and continuously rotating means operative to change communication between any of said passages and different channels, and operating so that, at any one time of operation, a multitude of the passages forms part of the path of flow of the fluid to be heated while another multitude of the passages forms part of the path of flow of the heating fluid, while still other passages are changing communication with respect to the channels and so that there is a continuous uniform flow of fluids through the heat exchange device and substantially no intermixture of the different fluids.
- 70 10. A regenerative heat exchange device comprising a frame-work containing a metal regenerative mass arranged to form a multitude of passages through the same, channels for a fluid to be heated and a fluid giving off heat, and means to provide relative 75 rotation of the frame-work and the channels to change communication between such of said passages and different channels, said means operating so that, at any one time of operation, a plurality of the passages forms 80 part of the path of flow of the fluid to be heated while another plurality of the passages forms part of the path of flow of the heating fluid and while still other passages 85 are changing communication with respect to the channels.
- 85 11. A regenerative heat exchange device comprising a cylindrical frame-work containing a metal regenerative mass arranged to form passages through the same, channels for a fluid to be heated and a fluid giving off heat, means to provide relative 90 rotation between the frame-work and the channels operative to successively change 95 communication between said passages and different channels, the arrangement being such that, at any one time of operation, a multitude of the passages on one side of the cylindrical frame-work forms part of the path of flow of the fluid to be heated while another multitude of the passages on the other side of the cylindrical frame-work forms part of the path of flow of the heating fluid and while still other passages, diametrically disposed with respect to the axis 100 of the cylindrical frame-work, are changing communication with respect to the channels.
- 105 12. A regenerative heat exchange device comprising a cylindrical rotor containing metal regenerative material having passages through the same, stationary channels for a fluid to be heated and a fluid giving off heat, means to rotate the rotor and operative to 110 change communication between any of said passages and different channels, the arrangement being such that, at any one time of operation, a plurality of the passages forms part of the path of flow of the fluid to be heated, while another plurality of the 115
- 120
- 125
- 130

passages forms part of the path of flow of the heating fluid and while still other passages, diametrically situated in the rotor, are changing communication with respect to the 5 channels.

13. A regenerative heat exchange device comprising walls forming compartments, supply and discharge channels for a fluid to be heated and a fluid giving off heat, means 10 to change communication between any of said compartments and different channels, metal regenerative material in said compartments comprising a multitude of metal elements extending in the same general direction and in the general line of flow through the compartments, said metal elements having ends which determine entrances and exits into and out of the regenerative material and being so constructed and arranged that continuous lines may be extended on the 15 surfaces of the elements from entrance to exit of the regenerative material, the arrangement being such that, at any one time of operation, a plurality of compartments form 20 part of the path of flow of the fluid to be heated, while another plurality of compartments form part of the path of flow of the heating fluid while still other compartments are changing communication with respect to 25 the channels, so that there is a continuous 30 uniform flow of fluid through the heat exchange device and substantially no intermix- 35 ture of fluids.

14. A regenerative heat exchange device comprising walls forming compartments, supply and discharge channels for a fluid to be heated and a fluid giving off heat, means 40 to change communication between any of said compartments and different channels, metal regenerative material in said compartments comprising a multitude of metal elements extending in the same general direction and in the general line of flow through the compartments, said metal elements hav- 45 ing ends which determine entrances and exits into and out of the regenerative material and being so constructed and arranged that continuous lines may be extended on the surfaces of the elements from entrance 50 to exit of the regenerative material, the arrangement being such that, at a given time of operation, a plurality of compartments form part of the path of flow of the fluid to be heated, while another plurality of 55 compartments form part of the path of flow of the heating fluid while still other compartments are momentarily out of communication with either path of flow as they change communication with respect to the 60 channels so that there is a continuous uniform flow of fluid through the heat exchange device and substantially no intermixture of fluids.

15. A regenerative heating device having 65 passages for fluids and wherein heat is ab- stracted from one fluid passing through the same and is given off to another fluid passing through the same, the fluid passing alternately through the same passages, said device comprising a frame-work, supply and 70 discharge channels for the fluid to be heated and the fluid giving off heat, means for effecting relative movement between said frame-work on the one hand and said supply and discharge channels on the other 75 hand, metal material in said frame-work to absorb and give off heat, said metal material consisting of a series of thin elements having relatively large surface in proportion to their volume so that a small 80 volume of heater is obtained for a large surface of heat absorption and rejection and means to prevent passage of gases from one channel to the other in all positions of relative movement. 85

16. A regenerative heating device having 90 passages for fluids and wherein heat is abstracted from a fluid passing through the same and is given off to another fluid passing through the same, the fluids passing alternately through the same passages, said device comprising supply and discharge channels for the fluid to be heated and the fluid giving off heat, a frame-work having a main body portion with open ends, 95 said open ends determining planes and a plurality of metal elements serving to absorb and give off heat and arranged in said frame-work perpendicularly to the planes of the open ends in the line of flow of gases 100 through the frame-work and means for effecting relative movement between said frame-work on the one hand and said supply and discharge channels on the other hand. 105

17. A regenerative heating device having 110 passages for fluids and wherein heat is abstracted from one fluid passing through the same and is given off to another fluid passing through the same, the fluids passing alternately through the same passages, said device comprising a frame-work, supply and discharge channels for the fluid to be heated and for the fluid giving off heat, means for effecting relative movement between said 115 frame-work on the one hand and said supply and discharge channels on the other hand, said frame-work having open ends determining planes and walls within said frame-work forming chambers, a plurality of 120 metal elements serving to absorb and give off heat arranged in said chambers perpendicularly to the planes of the open ends and in the line of flow of gases through the frame-work, plates arranged at the ends of said 125 walls, said frame-work and plates having relative movement and said plates being of such size as to cover each of said chambers 130 successively as the chambers change communication with respect to the channels so

that passage of fluid from one channel to the other is prevented in all positions of relative movement.

18. A regenerative heating device having 5 passages for fluids and wherein heat is abstracted from one fluid passing through the same and is given off to another fluid passing through the same, the fluids passing alternately through the same passages, said device comprising supply and discharge channels for the fluid to be heated and the fluid giving off heat, a frame-work having open ends, said open ends determining planes, a series of metal plates serving to absorb and 10 give off heat arranged in said frame-work perpendicularly to the planes of the open ends and parallel to the line of flow of gases through the frame-work and means for effecting a relative movement between the 15 frame-work on the one hand and said supply and discharge channels on the other hand.

19. A regenerative heating device for fluids wherein heat is abstracted from one fluid passing through the same and is given 20 off to another fluid passing through the same, said device comprising supply and discharge channels for the fluid to be heated and the fluid giving off heat, a frame-work, walls in said frame-work forming chambers, a series 25 of metal plates in said chambers, said frame-work having open ends, said open ends determining planes, said plates being arranged perpendicularly to the planes of the open ends and of such form as to provide a series 30 of continuous parallel passages of substantially uniform cross-section through said frame-work for the passage of fluids, and means for effecting relative movement between said frame-work on the one hand and 35 said supply and discharge channels on the other hand so that the fluids pass alternately 40 through the same passages.

20. A regenerative heating device having 45 passages for fluids and wherein heat is abstracted from one fluid passing continuously through the same and is given off to another fluid passing continuously through the same, the fluids passing alternately through the same passages, said device comprising a frame-work, supply and discharge 50 channels for the fluid to be heated and the fluid giving off heat, means for effecting relative movement between said frame-work on the one hand and said supply and discharge 55 channels on the other hand, said frame-work including walls forming chambers, regenerative material in said chambers, plates arranged at the ends of said walls, said frame-work and plates having relative movement 60 and said plates being of such size as to close each of said chambers successively as the chambers change communication from one channel to the other so that passage of fluid from one channel to the other is prevented 65 at all times.

21. A regenerative heating device comprising a series of heat exchange units, each comprising a plurality of metal elements forming a passageway system comprising a plurality of passages, means to alternately pass different fluids through the same said passages, and means to isolate a portion of the passageway system at certain times when there is a change of fluids with respect to 70 said portion of the passageway system. 75

22. A regenerative heating device comprising a series of heat exchange units, each comprising a plurality of metal plates arranged to form a passageway system comprising a plurality of passages of substantially uniform cross-section, means to alternately pass different fluids through the same said passages and means to isolate a portion of the passageway system at certain times when there is a change of fluids with respect 80 to said portion of the passageway system. 85

23. A regenerative heat exchange device comprising a cylindrical frame-work, a series of equally spaced radial walls dividing said frame-work into a series of chambers, metal regenerative material in said chambers serving to subdivide said chambers into a multiplicity of small passages for flow of fluid, and channels for passing heating and heated fluids alternately through the same 90 said passages. 95

24. An apparatus of the class described comprising a plurality of chambers each having therein a multiplicity of thin metal heat exchanging plates having a large ratio 100 of surface to volume and means for automatically passing hot gases in contact with said plates for a determined period and then passing air to be heated in contact therewith for another period, said heat exchanging plates being arranged to extend in the general line of flow of fluid through the 105 chambers.

25. An apparatus of the class described comprising a plurality of chambers each 110 having therein a multiplicity of nested heat exchanging plates having a large ratio of surface to volume and automatically controlled means for alternately passing hot 115 gases and cool air in contact with said plates for determined periods of time, the apparatus being so arranged that the waste gas flows continuously therethrough in one direction and the air to be heated also flows continuously in one direction, said plates forming a multitude of parallel passages of uniform cross-section in the general line of 120 flow of fluid through the chambers. 125

26. A regenerative heating device comprising a series of heat exchange units, each comprising a plurality of metal elements forming a passageway system comprising a plurality of passages, means to alternately pass different fluids through the same said 130 passages, and means to isolate a portion of

the passageway system at certain times when there is a change of fluids with respect to a portion of the passageway system, said metal elements being arranged to extend in the 5 general line of flow of fluid through the device and having a large ratio of surface to volume.

27. A regenerative heat exchange device comprising supply and discharge channels 10 for a fluid to be heated and a fluid giving off heat, a metal regenerative mass arranged to form a multitude of passages through the

same, means to successively change communication between said passages and channels, the arrangement being such that at all times 15 there is a multitude of said passages forming part of the path of flow of fluid to be heated and a multitude of passages forming part of the path of flow of the heated fluid and means to successively isolate the 20 passages when changing communication with said channels.

In testimony whereof I affix my signature.

FREDRICK LJUNGSTRÖM.
